[57] CLAIM

The ornamental design for a sunglass temple, as shown and described.

DESCRIPTION

FIG. 1 is a left front perspective view of a left sunglass temple of the present invention, the right side sunglass temple (shown in broken lines) being a mirror image thereof;

FIG. 2 and is a top plan view thereof;

FIG. 3 is another top plan view thereof;

FIG. 4 is a left side elevation view thereof;

FIG. 5 is a bottom plan view thereof;

FIG. 6 is a right side elevation view thereof;

FIG. 7 is a front end elevational view thereof; and,

FIG. 8 is a rear end elevational view thereof.

The broken lines showing the sunglass lens and lens frame portions in FIGS. 1 and 2 are for illustrative purposes only and form no part of the claimed design.
